UNITED STATES PATENT OFFICE.

PHILIP C. WENTWORTH, OF PROVIDENCE, RHODE ISLAND.

RING TRAVELER.

1,415,070.

Specification of Letters Patent.

Patented May 9, 1922.

Application filed June 4, 1921. Serial No. 474,987.

To all whom it may concern:

Be it known that I, PHILIP C. WENTWORTH, a citizen of the United States, residing at Providence, county of Providence, State of Rhode Island, have invented certain new and useful Improvements in Ring Travelers, of which the following is a specification.

This invention relates to ring travelers for use in ring spinning or twisting and particularly to the construction of such a device in such manner as to avoid or eliminate the loading of the traveler by lint or fly or otherwise.

My invention contemplates the construction of a traveler which in its operation will avoid this loading and thus maintain the traveler at its desired weight, thus making clearing or cleaning unnecessary as my traveler at all times remains clean.

The construction and operation of my traveler, together with a selected embodiment which well illustrates the principles involved, is described and illustrated in the accompanying specification and drawings, and the characteristic features of novelty particularly pointed out in the appended claims.

Throughout the specification and drawings like reference characters are employed to indicate corresponding parts, and in the drawings:

Figs. I and II and III, respectively, are side, end and top views of a traveler in accordance with my invention.

Fig. IV is a diagrammatic view illustrating the position of the traveler on the ring relative to the spindle, and

Fig. V a fragmentary view of a ring with traveler positioned thereon as in operation.

I have shown in the drawings a standard type of traveler comprising a center or circle portion 1 and a terminal or end portion or horns 2. The circle portion is provided with one or more annularly disposed vent openings 3 therethrough the effect of which is to permit a draft directly into the traveler itself and substantially transverse to the circle or bow portion 1, over which the fibres of the load tend to drape themselves in their normal accumulating effect, and this draft upon striking the fibres of the load at this place clears the traveler of the accumulated lint.

The ring is indicated diagrammatically in Figs. IV and V at R, the spindle at S, the thread at Y and the traveler at 1.

What I therefore desire to secure by Letters Patent is:

1. A ring traveler comprising an annular body provided with openings.
2. A ring traveler comprising a body provided with annularly disposed openings.
3. A ring traveler comprising an annular body provided with round openings.
4. A ring traveler comprising a body provided with annularly disposed round openings.

In testimony whereof I affix my signature in presence of a witness.

PHILIP C. WENTWORTH.

Witness:

GEO. B. RAWLINGS.
